3 SHEETS—SHEET 3.

UNITED STATES PATENT OFFICE.

HENRY RUINELLO, OF JERSEY CITY, NEW JERSEY.

RAILWAY-GATE.

1,266,321.

Specification of Letters Patent. Patented May 14, 1918.

Application filed June 14, 1917. Serial No. 174,646.

To all whom it may concern:

Be it known that I, HENRY RUINELLO, a citizen of the United States, and a resident of Jersey City, in the county of Hudson and State of New Jersey, have invented a new and Improved Railway-Gate, of which the following is a full, clear, and exact description.

This invention relates to railway gates and has for an object the provision of an improved construction which may be operated by the train so as to present a barrier and operated manually to a restored position.

Another object in view is to provide a gate which presents a positive barrier against vehicles and which will yieldingly resist a forward movement of the vehicles in case of contact therewith.

A further object in view is to provide a railway gate which will normally lie flat in the road but when released will move pivotally upwardly to a vertical position across the road.

In the accompanying drawings:

Figure 1 is a top plan view of a pair of gates and associated parts disclosing an embodiment of the invention.

Fig. 2 is a section through Fig. 1 on line 2—2.

Fig. 3 is a view similar to the left part of Fig. 2 except that the parts are shown in a different or operated position.

Fig. 4 is a fragmentary sectional view through Fig. 3 on line 4—4.

Fig. 5 is a detail fragmentary sectional view through Fig. 2 on line 5—5.

Fig. 6 is an enlarged detail side view of one of the train engaging rails, certain parts being broken away for better illustrating the construction.

Fig. 7 is an enlarged fragmentary sectional view through Fig. 1 approximately on line 7—7.

Fig. 8 is a view similar to Fig. 3 but disclosing a slightly modified form of the invention.

Fig. 9 is a view similar to Fig. 8 but showing the opposite side of the track and disclosing a further modified form of the invention.

Fig. 10 is a detail fragmentary horizontal sectional view through Fig. 9 on line 10—10.

Fig. 11 is a view similar to Fig. 8 but disclosing a slightly modified form of the invention.

Fig. 12 is a view similar to Fig. 11 but showing a further modified form of the invention.

Referring to the accompanying drawings 60 by numerals, 1 and 2 indicate rails for accommodating trains running in opposite directions, rail 1 being designed to accommodate a train running in the direction of the arrow 3 while rail 2 accommodates a 65 train running in the direction of the arrow 4. When the train reaches the auxiliary rail near the crossing 5 both of the gates 6 and 7 are released and caused by mechanism hereinafter fully described to be 70 moved upwardly pivotally as shown, for instance, in Fig. 3, whereby vehicles cannot pass and also pedestrians cannot pass by reason of the sidewalk gates 8, 9, 10 and 11 shown in detail in Fig. 4. As both the 75 gates 6 and 7 are identically constructed a description of one will apply to both.

When a train is passing over track 1 and nears the crossing 5 one of the wheels will strike the auxiliary rail 12, shown in detail 80 in Fig. 6, and will depress the same, said depressing movement being also a longitudinal movement by reason of the links 13 and 14, said longitudinal movement giving the connecting rod 15 a push so that the bar 16 will be moved longitudinally against the action of the spring 17 and, consequently, the bell crank lever 18 (Fig. 1) will be moved so as to move the pin 19 extending through the slot 20 in the enlargement or 85 plate 21 of the rod 22. This will cause the rod 22 to be given a movement as indicated by the arrow 23, and as said rod is connected to the catch 24 (Fig. 7) said catch will be withdrawn from contact with the 90 gate 6 and said gate will, by reason of the weight 25 connected thereto, move to the position shown in Fig. 3. Catch 24 is provided with a hollow portion 26 so that the head 27 of the rod 28 may pull said catch 95 when rod 22 is pulled but said catch may be acted upon by the gate 6 and forced downwardly pivotally against the action of spring 29 without affecting the position of rod 22. By this construction and arrangement whenever the front wheel of the train strikes the auxiliary rail 12 gate 6 will be released so as to move to the position shown in Fig. 3 and also gate 7 will be released, as the rod 22 extends to the catch 24 of gate 100 7. The gate 6 is pivotally supported by rod 30 so that one end is in the pit 31, said end

carrying the weight 25. This weight is intended to be sufficiently heavy to move the gate 6 to the position shown in Fig. 3 and also to transmit power to the other parts 5 of the device, including the sidewalk gates and the connecting cable 32 which connects gate 6 with gate 7.

The sidewalk gates are of identical construction so that a description of gate 9 will 10 apply to all, said gate being arranged as shown in Fig. 4, with an arm 33 extending across the sidewalk 34, said arm being pivotally mounted on a rod 35 and carrying a guiding pulley 36 over which the cable 37 passes, said cable carrying a weight 38. Cable 37 is connected at 39 to arm 33 so as to move said arm back to a vertical position when the gates 6 and 7 are closed. When the gate 6 is moved to an open position the 20 same pulls on the cable 40 which is secured at 41 to the weight 25, said cable passing over pulleys 42, 43 and 45 whereby the free end may be secured at 46 to arm 33 for pulling said arm to a lowered position.

25 In addition to gate 6 operating the sidewalk gate 9, said gate has a cable 47 connected thereto at 48, said cable passing over a drum 49 arranged in a suitable casing 50. The cable or rod 32 passes over part of the 30 drum 49, as shown in Fig. 5, so that when gate 6 is released and moves upwardly the cable 47 will be unwound and likewise the cable 32 will be unwound, said cables in turn winding on the drum 51 on the opposite side 35 of the rails as the gate 7 moves upwardly. A sprocket wheel 52 is secured to drum 49, said sprocket wheel accommodating chain 53, which chain is passed over an upper sprocket 54 carrying a crank 55 whereby 40 when crank 55 is rotated manually drum 49 may be turned so as to wind cable 47 and also cable 32, thus pulling the gates 6 and 7 downwardly until the catches 24 snap thereover. It will be noted that by reason of the 45 auxiliary rails 12 and associated parts a train approaching the crossing will automatically release the gates and they in turn will automatically move upwardly and present a barrier both for pedestrians and vehicles. The gates will remain in their raised position until some one manually operates one of the cranks 55.

50 In Fig. 8 will be seen a slightly modified form of the invention in which the same 55 general idea is followed with a slightly different construction of lifting means provided, said lifting means comprising an arc-shaped rack 56 secured to the gate 6, said rack meshing with a pinion 57, said pinion 60 in turn being rigidly secured to the shaft 58 carrying a sprocket 59 over which the chain 60 passes, said chain also passing over an upper sprocket 61 secured to the crank 62. The pinion 57 is preferably wide enough 65 to engage the rack 63 on the transverse bar

64 but, if desired, a separate pinion could be used and secured to shaft 58 whereby a larger or smaller gear could be utilized for increasing or decreasing the ratio of movement.

70 In Fig. 9 a further slightly modified form of the invention is shown which is very similar to Fig. 8 with the exception that the watchman's house 65 may be utilized if desired. Arranged in the house 65 or adjacent thereto is a manually operated lever 66 which is connected with rod 67, said rod in turn being connected with a horizontally positioned lever 68 having a slot 69 arranged therein (Fig. 10), said slot accommodating 80 pin 70 secured to the rod 71, said rod being connected to catch 24, as shown in Fig. 7 of the preferred form, and so will need no additional description. From this construction and arrangement it will be observed 85 that the gate 7 and also the opposite gate when formed in this manner are released manually instead of by the train. However, in this form of the invention the gates are returned in a similar manner to that shown 90 in Fig. 8.

95 In Fig. 11 will be seen a further modified form of the invention in which the gate 6 is released by the operation of the lever 66' similar to lever 66, said lever 66' and connected parts being constructed similar to that shown in Figs. 9 and 10. The modified structure consists of having the cable 72 connected with drum 73 so as to be wound thereon when the electric motor 74 is in operation, said motor being connected with the drum 73. The motor 74 is connected to a source of current 75 and also to a manually operated switch 76 preferably arranged in the watchman's house 77 whereby the watchman may close the gate 6 by merely closing the switch 76 and as soon as the gate has passed beneath the catch the switch is to be opened.

100 In Fig. 12 is shown a further modified form of the invention in which the gate 6 is lowered by the use of hydraulics, the same 110 consisting of a cylinder 78 having a piston 79, said piston being connected with rod 80, said rod being pivotally connected to gate 115 6, while the cylinder 78 is pivotally connected at 81 to a suitable support in the pit 82. A flexible cable 83 is connected to the cross pipe 84 and to the upper part of cylinder 78 120 so that whenever the valve 85 is turned on water in tank 86 will enter pipe 84 and be distributed through hose 83 to cylinder 86 for pulling on piston rod 80 and moving the gate 6 to a closed position. Some of the 125 water will pass through the pipe 84 to the opposite side and operate the gate on said opposite side. In order to provide power for the water any suitable pump 87 may be used for pumping air in the upper part of the tank, and when it is desired for the wa- 130

ter to return into the tank 86 air valve 88 is opened which exhausts the air which will allow the weight 25 to return the parts to the position shown in Fig. 2, including the 5 returning of the water to tank 86.

In Figs. 8, 9, 11 and 12 are disclosed modified forms utilizing different means of restoring the gate 6, but in all these forms it will be observed that the gate 6, weight 25 10 and the connections for the sidewalk gates are the same. It is also evident that all these gates could be released by the train operating mechanism shown in Fig. 1 or by the particular mechanism shown in the various figures without affecting the return 15 mechanism.

What I claim is:

1. A railway gate comprising a gate formed of solid material and adapted to 20 normally lie flush on the roadbed, said gate being of substantially the same width as the railway bed and having an extension at one end, a pit for receiving said extension, a weight arranged on said extension, means 25 for pivotally supporting said gate whereby when the gate is released said weight will swing the gate to a substantially vertical position, a pair of sidewalk gates, means connecting said sidewalk gates with the first 30 mentioned gate so that when the first mentioned gate is moved to a substantially vertical position the sidewalk gates will be moved to a substantially horizontal position, and a catch for normally holding said first 35 mentioned gate against movement.

2. A railway gate comprising a gate member, means engaging said gate member between the ends for pivotally supporting the same, means defining a pit, one end of 40 said gate member extending into said pit, a weight connected to said last mentioned end, a sidewalk gate having a pivotal arm, a cable connecting said weight with said arm, means for guiding said cable whereby when 45 said gate member is moved to a vertical position said arm will be moved to a substantially horizontal position, a catch for holding said gate member normally in a

substantially horizontal position, and means acting on said catch for releasing the same. 50

3. A railway gate comprising a pair of gate members adapted to normally lie flush on the road bed, on opposite sides of a railway, each of said gate members being provided with an extension at one end, a pit 55 for each gate member for receiving said extension, a weight arranged on each of said extensions, means for pivotally supporting each of said gate members whereby when the gate members are released said weight will 60 swing the gate members to a substantially vertical position, a cable connected to each of said gate members, a drum connected to said cables, a connecting cable secured to each of said drums, means adjacent each of 65 said drums for rotating the same and winding the cables connected with said gate members, whereby when either of said last mentioned means is operated said drums will be rotated and both of said gate members will be moved against the action of 70 said weights to a position substantially flush with the road-bed, and a catch for normally holding said gate members against movement. 75

4. A railway gate comprising a pair of gate members adapted to normally lie flush on the roadbed, on opposite sides of the railway, a catch for each of said gate members for normally holding the same against said 80 roadbed, a single rod extending from one catch to the other, means for connecting the opposite ends of said rod to said catches so that when said rod is moved in one direction both the said catches will be moved to release the gate members, means operated by a train for moving said rod in such direction as to release said catches, means for pivotally supporting each of said gate members, each of said gate members having an 85 extension at one end, and a weight arranged on said extension whereby when said catches release said gate members they will automatically move to a substantially vertical 90 position.

HENRY RUINELLO.
